MAURICE A. METCALF, OF BOSTON, MASSACHUSETTS.

TEMPLE DEVICE FOR LOOMS.

1,230,792.

Specification of Letters Patent. Patented June 19, 1917.

Application filed March 21, 1916. Serial No. 85,736.

To all whom it may concern:

Be it known that I, LITFALLAH G. SABBAG, a citizen of the United States, and resident of Boston, in the county of Suffolk and State of Massachusetts, have invented new and useful Improvements in Temple Devices for Looms, of which the following is a specification.

My invention relates to a temple stand 19 and temple for looms.

One object of my invention is to provide a simple, cheap and durable device adapted to be readily adjusted by unskilled persons, which shall be more efficient than present 15 types of temple with respect to the prevention of shrinkage in width from the tension of the weft, and which shall be free from any tendency to damage the cloth, as by puncturing, tearing, or detaining and pulling 20 ing on projecting ends of yarn.

Loom temples of the prior art comprising rotating devices of one sort or another held by a pod, stand or other mounting in such a manner as to engage the cloth between 25 the point reached by the forward stroke of the lay and the breast beam, the position of the axis and the conformation of the roll forming the temple proper being relied upon to strain the cloth laterally 30 with respect to its direction of travel to the take-up rolls, are all, so far as I am aware, defective because of clogging and stoppage due to the stray ends or projecting yarns 35 always found in greater or less quantity near the selvage of the new cloth. It is practically impossible to avoid the entrance of an occasional stray yarn between the temple roll proper and its stud, gudgeon or bearing, whereupon the yarn wraps around 40 the bearing or roll, often stops the rotation of the temple proper, and often causes damage to the cloth in the best practice of which I am aware.

It has heretofore been proposed to shear 45 yarns projecting from the selvage ahead of the temple, but while this procedure has resulted in reducing in volume the annoyance and damage mentioned, none of the devices of the prior art, so far as I am aware, are 50 wholly successful in avoiding grasping an occasional projecting end and damaging the cloth at this point, sometimes beyond repair.

In one aspect my invention relates to the 55 provision of means for maintaining the

cloth under a lateral strain by the use of relatively stationary devices with respect to which the take-up and growth movement of the cloth reacts to place the cloth under a lateral stretching strain. My invention also relates to the provision of an improved mounting or stand for the stud or other temple devices, and to a weft severing device operating in conjunction with the temple proper so as to shear from the 60 cloth projecting wefts or other waste yarns 65 extending beyond the selvage.

In the accompanying drawings,

Figure 1 is a side elevation of the right hand temple of a like but symmetrically 70 opposite pair, showing the breast beam in section;

Fig. 2 is a detail view similar to Fig. 1, but showing the lay at the forward extremity of its throw, and showing the weft severing means in another position;

Fig. 3 is a plan view;

Fig. 4 is a detail plan of the cap or cover;

Fig. 5 is a plan illustrating a symmetrical pair of opposite temples;

Fig. 6 is a detail elevation corresponding to Fig. 1, the severing device being removed;

Fig. 7 is a diagram elevation from the center of the loom illustrating the operation 85 of the temple rolls;

Fig. 8 is a right hand elevation of the devices shown in Fig. 1; and

Fig. 9 is an elevation partly in section 90 illustrating a modification.

Referring now to Fig. 1, on a convenient place in the loom, for instance the breast beam 1, a mounting 2 comprising a base 3 and a bearing 4 is mounted for adjustment so that a longitudinal bore in the bearing 4 stands longitudinally of the direction of travel of the forming cloth, at the desired distance from the center of the loom on each side thereof. Preferably the base 3 is slotted for hold-down screws 5, and one preferred form of adjustment is that shown in Fig. 3 in which counter-sinks 6 in the base 3 are connected by a slot 7 so that the screws 5 may be loosened and the base 3 adjusted to conform to a different width of 100 cloth, without changing the direction of the bearing 4. Sliding freely in the bore in the bearing 4 a threaded stem 10 is provided with lock nuts 11 and with keying means to prevent rotation of the stem 10 110

in the bearing 4, for instance as shown, being provided with a screw or pin 12 working in a slot 13 in the bearing 4. A compression spring 14 reacting with an integral or attached head 15 on the stem 10 maintains the stem 10 to the right of Figs. 1 and 3.

The temple proper is carried by a mounting integral with or attached to head 15, 10 which may be provided with a depending lug 16 adapted to be struck by the lay 18 at the forward extremity of its beat.

By the construction described, the motion of the temple carried by the head 15 of the 15 stem 10 in a direction contrary to the motion of the cloth or like the direction of growth of the cloth is caused by the spring 14, and the extent of this motion (which takes the temple to a new place in the cloth 20 at each beat of the lay) is adjusted by the lock nuts 11. I have found in practice that structures usual in the art for mounting temples and comprising integral restraining means corresponding to the lock nuts 25 11 are soon rendered useless by wear, the adjustment at 11 for the backward position of the temple mounting being of importance to the correct operation of any form of temple.

30 In order to avoid the defect of the clogging of rotating rolls, as mentioned above, the temple carried by the mounting 10, 15 is preferably provided with fixed elements serving to stretch the cloth outwardly with 35 respect to the center line of the loom. I have devised means for this purpose characterized by the absence of parts puncturing or penetrating the cloth and adapted to firmly grasp the edges of the cloth. One preferred form of this means is illustrated in 40 Figs. 5, 6 and 7, comprising (see Fig. 7) a staggered series of fixed grooved bodies 20, 21, preferably comprising screw-threaded cylinders as shown, so placed that a line 45 tangent to the peripheries of an upper series 20 intersects one or more of the lower series 21. The bodies 20, 21 do not touch, but may be separated so that the path of the cloth *a* between the series 20 and the series 50 21 is sinuous as shown in Fig. 7. Any number of bodies 20, 21 may be provided, as desired.

For that temple on the right-hand side of the loom (that one shown in Fig. 3 and at 55 the bottom in Fig. 5) the bodies 20 have grooves sloping to the left, as by making them as left-handed screws, and the bodies 21 have right-hand sloping grooves, such as right-hand screw threads. For the other temple, the arrangement of grooved surfaces is opposite.

The respective bodies 20 and 21 are fixed, but preferably not immovably fixed, in a pod or casing 22 integral with or attached 65 to the head 15 on the stem 10, said casing

preferably having a bottom surface 23 protecting the rolls at the under side.

A cover 24 forms a part of casing 22, for instance by attachment on a flat 25 by a screw 26 tapped into the casing 22 and an adjusting screw 27 taking against the flat 25. The cover 24 may have the usual positioning lip 28.

In some cases I prefer to render the distance between the rolls or bodies 20 and the 75 rolls or bodies 21 adjustable, and I may provide any convenient means for this purpose, for instance as shown in Fig. 9, by providing on the cover 24 a depending lug 29 having bores for the rolls 20, the casing 22 being suitably recessed to admit the lug 29. The distance between the bodies 20 and 21 may thus be adjusted by adjustment 80 of screw 30 in a threaded hole in cover 24 and lug 29, taking against casing 22, 85 the position of the rolls being locked by screw 26.

One convenient means as shown for mounting of the grooved bodies 20, 21 is to screw their ends in tapped holes in the casing 90 22, the outer ends of said rolls being provided with slots for a screw driver as shown in Figs. 6 and 9, but in some cases I may reduce the outer ends of the rolls and insert them in holes either tapper or un-tapped in the casing 22, and I may provide 95 any convenient means for adjusting, rotating or fixing against rotation the rolls or bodies 20, 21, which in any case are stationary in a rotative sense in operation. By 100 the illustrative construction I am enabled to rotate them in their bearings in the casing 22 to present a fresh wear surface after long use.

In use, the cloth *a* is run between the 105 rolls 20 and the rolls 21, and by its relative motion with respect to the temple mounting, the cloth is placed under an outward strain with respect to the center of the loom by the directive action of the screw 110 threads on the respective rolls 20 and 21. The longitudinal tension on the cloth is sufficient to cause it to follow the contour of the threaded rolls or bodies, and so to provide in the cloth a series of ridges or 115 creases at the part in contact with the temple permitting longitudinal movement, but which the ordinary lateral strains of beat-up and take-up can not release, my temple in action proving its resistance to diminution of the width of the cloth to be superior 120 to that of temples relying upon puncturing devices, but with the advantage that no destructive strain is put upon the cloth.

The gage and form of inclined grooves, 125 such as the spiral threads of the round rolls 20 and 21 may be varied in accordance with the cloth under manufacture, but I find in practice that quarter-inch rolls threaded 12 to the inch, for one instance only, are prac- 130

ticable for a wide range of cotton cloths, the temple specified having the characteristics above noted.

One advantage of my device lies in the freedom from any possibility of entanglement with the rolls 20, 21 of loose ends, there being no moving parts capable of wrapping an end into a bearing. But I nevertheless find it desirable to provide for cutting projecting wefts or other waste at the selvage, and for this purpose I am able to utilize the strong hold taken upon the cloth and upon the weft with relation to the warp in the cloth to enable cutting the waste ends at the temple in a superior manner.

Not only the cloth but the wefts within the cloth being held at passage of the rolls 20 and 21 under restraint against lateral movement in either direction, I am able to cut the projecting weft by gripping it at a point separated from the selvage and then cutting the run of yarn between the selvage and the point at which it is gripped. Pivoted on a shoulder screw 35 fast in the casing 22, a gravity lever 36 having a heavy cam-end 37 in the path of the lay 18 is provided with a sharpened depending knife blade 38. When the lay beats forward, the lever 36 is rocked downward to give the blade 38 a cutting stroke, for instance carrying it through the plane of the cloth. Surrounding the screw 35, to be actuated by the lever 36, (as by having an end entering a hole 39 of the lever) I provide a resilient gripping device 40 which may be made as shown of spring-wire carrying in a loop at one end a yielding block 41 of rubber, felt, leather or the like.

Integral with or attached to the cover 24 I provide an anvil 42, for instance as shown by a downward and outward bend 43 of a thin integral extension of the material of the cover 24. The casing 22 is provided with a slot 44 having if desired a flared mouth, adapted to receive a projecting weft or other end, as the cloth moves into the temple, and preferably I provide the anvil 42 with a downwardly and inwardly bent extension 45 to direct the yarns above anvil 42 and so placed as to give free play to the blade 38 of lever 36, as shown. One or both temples may be provided with cutters and clamps as described.

By the described constructions, relative motion of the cloth presents the loose ends at the selvage in the slot 44 and over the anvil 42. Upon the next beat of the lay after entrance of such a waste end, the block 41 is first brought down upon the waste end, and the lever 36 is then further actuated to cut the tautly held waste yarn. The cloth to which the waste yarn is attached is meanwhile crinkled or crimped in the grip of the bodies 20, 21, so that the

operation of the blade 38 is of no effect to pull a weft or damage the cloth.

It will be observed that the stretching pull on the cloth, by my device, is between the areas measured by the length and width of the cloth *a* in engagement with the bodies 20, 21. This area is larger than in any prior temple device of which I am aware, and I am thereby enabled to exert a greater strain on weak cloth than has been heretofore possible, while preventing injury to the cloth in the manner described.

While I have described and shown rotatable bodies 20, 21, it will be understood by those skilled in the art that the active surfaces of said bodies are those contacting with the cloth, and that in some cases the bodies 20 or 21, or both, may be segments of cylinders or other solid forms not rotund as shown, and that the respective bodies 20, 21 may in that case be mounted throughout their length on or be integral with surfaces of a casing 22 and a cover 24, by which the respective bodies are held in the relation to each other and the cloth *a* above explained.

For convenience of illustration, I have shown the severing device mounted on but one of the temple devices, but I contemplate providing similar severing means on both temples when desirable or necessary, especially in looms providing for holding a shuttle or shuttles idle at each side of the cloth. While I have mentioned severing projecting wefts, it will be understood that my device readily picks up and severs as well any component yarn projecting at the selvage and liable to be caught and pulled at the temple.

What I claim is:

1. A loom having a breast beam for determining the position of the cloth, in combination with independent mountings at each side of the cloth, each having fixed thereto means adapted to determine a series of temporary folds or ridges at and near the respective selvages of the cloth only, said folds or ridges lying longitudinally of but at an angle to the direction of progress of the cloth, whereby relative movement between the cloth and said means causes the cloth to be strained laterally.

2. A loom having a lay and a breast beam for determining the position of the cloth, in combination with independently yielding mountings at the sides of the cloth adapted to be moved upon the forward beat of the lay and each having fixed thereto means adapted to determine a series of temporary folds or ridges at and near the respective selvages of the cloth only, said folds or ridges lying longitudinally of but at an angle to the direction of progress of the cloth, whereby relative movement between the cloth and said means causes the cloth to be strained laterally.

3. A loom having therein a breast beam for determining the position of the cloth, and temples each comprising a mounting, bodies having a series of surface grooves or 5 ridges therein, and means for supporting on said mountings fixedly with respect to each other a plurality of said bodies respectively in contact with the opposite sides and at and near the selvages only of the cloth positioned 10 by said breast beam, said mountings being adapted to position said grooves or ridges at an angle to the direction of progress of the cloth through the loom, whereby to determine an outward strain upon the edge 15 of the cloth with respect to the free longitudinal central portion thereof.
4. A temple device for looms comprising three or more rounded free-ended bodies adapted to contact with and direct the 20 woven cloth having surfaces comprising grooves for contact with the cloth all inclined in the same direction, and means fixedly holding said bodies out of contact with each other and with the grooved surfaces 25 of one or more thereof intersecting a plane defined by the surfaces of the others.
5. A temple device for looms comprising a series of free-ended bodies having inclined grooves arranged in staggered relation, 30 whereby cloth may be passed sinuously between said bodies, and means adapted to yield in the direction of motion of the cloth for holding said bodies relatively fixed in relation to each other, whereby stress upon the 35 cloth is resisted by said bodies in one direction more than in another.
6. A temple device for looms comprising three or more free-ended grooved bodies and means for holding them fixed in relation to 40 each other in separated staggered relation, to admit the cloth sinuously between said bodies, and means for supporting said holding means and grooved bodies whereby lateral stress upon the cloth is resisted by the 45 grooves in said bodies and longitudinal relative movement between said bodies and the cloth is permitted.
7. A loom temple comprising a casing, a plurality more than three of free ended 50 bodies fixedly held in relation to each other in said casing to leave a free sinuous path between said bodies for one edge of the cloth, said bodies having grooved surfaces, the grooves on each side of the path for the cloth being inclined in the same direction.
8. A loom temple comprising a casing and cylindrical bodies fixed for rotative adjustment in said casing to leave a free sinuous
- path between said bodies for the cloth, said bodies having grooved surfaces, the grooves 60 on each side of the path for the cloth being inclined in the same direction.
9. A temple device for looms comprising a casing, a series of normally fixed bodies having grooves on the surface thereof mounted in said casing, a cover removable normally fixed for said casing, and a coöperating series of similarly and oppositely grooved bodies fixed to said cover whereby, when the parts are assembled a sinuous path 70 for cloth contacting on each side thereof with said grooved surfaces is provided.
10. In a temple device for looms the combination of a temple stand and a casing adapted to yield longitudinally in the direction of travel of the cloth in combination with fixed bodies in said casing having grooves adapted to engage the cloth respectively on opposite sides and inclined to the direction of motion of said mounting. 75
11. A loom having in combination a breast beam, a lay, and means adapted to be mounted on the breast beam comprising a longitudinal bearing, a stem therein, an adjustable stop on the stem, a compression spring 80 reacting between said bearing and a head on said stem, a casing fixed to said head, fixed grooved bodies in said casing for directing the progress of the cloth in contact with said bodies, and a lug carried by said stem adapted to be struck by the lay. 85
12. A yarn cutting temple device for looms comprising a temple casing, a clamp device comprising an anvil spaced away from said casing, a severing blade working 90 between said anvil and casing and out of contact with either, and means for operating said clamp device and said severing blade adapted first to close the clamp on a yarn, and thereafter to sever the yarn. 95
13. A severing device for coöperation with a loom temple comprising a casing, an anvil separated from said casing, a gripper device comprising a spring arm and resilient member adapted to compress a yarn 100 on said anvil, a severing blade made as a lever having a cam end adapted to be actuated by a moving part of the loom said blade being pivoted to enter between said anvil and casing, and means connecting said lever and spring arm adapted to close the gripper prior to severing a yarn lying on said anvil. 110

Signed by me at Boston, Massachusetts,
